[57] CLAIM

The ornamental design for a musical instrument digital
interface plug, as shown and described.

DESCRIPTION

FIG. 1 is a perspective view of a musical instrument
digital interface plug showing my new design;

FIG. 2 is an end view thereof;

FIG. 3 is a sectional view taken along line 3—3 of FIG.
1;

FIG. 4 is a top plan view thereof;

FIG. 5 is a right side elevational view thereof, the left
side elevational view thereof being a mirror image;

FIG. 6 is a bottom plan view thereof.

FIG. 2

FIG. 3

FIG. 4

FIG. 5

FIG. 6
